UNITED STATES PATENT OFFICE.

EDWIN F. BANFIELD, OF NEW YORK, N. Y.

ELEVATOR CONTROL.

1,293,668.

Specification of Letters Patent. Patented Feb. 11, 1919.

Application filed November 21, 1913. Serial No. 802,181.

To all whom it may concern:

Be it known that I, EDWIN F. BANFIELD, a citizen of the United States, and a resident of the city of New York, in the county of 5 New York and State of New York, have invented certain new and useful Improvements in Elevator Control, of which the following is a specification.

This invention relates to improvements in 10 elevator controls.

One of the objects of the invention is to provide an improved elevator control wherein the operation of the elevator car is impossible unless the car door is closed.

15 Another object is to provide an improved elevator control wherein the car is stopped whenever the car door is opened.

Another object is to provide an improved elevator control wherein both the car door 20 and the shaft door must be closed before the elevator can be operated.

Another object is to provide an improved elevator control wherein the operator may stop the car in any position in the shaft by 25 merely opening the car door.

Another object is to provide an elevator control, under the influence of the car door, which dispenses with the necessity for a 30 multiplicity of electrical circuit contacts and connections at the elevator landings or within the car.

A further object is to provide an improved elevator control wherein the control devices are not readily accessible to the car operator and consequently cannot be easily rendered inoperative to allow the car to be run 35 without the door thereof being closed.

Another object is to provide an elevator control which is simple, reliable and efficient.

Other objects and advantages of the invention will appear from the following description and claims.

In the embodiment of the invention illustrated in the accompanying drawings, a 45 flexible cable, extending along the elevator shaft, is mechanically controlled by the operation of the car door to control the application of the driving power to the car so 50 that the car cannot be started until the door thereof is closed and may be stopped by the simple act of opening the door regardless of the condition of the operator's ordinary means of control. As a further security 55 against accident there is provided an interlock between the car and shaft doors where-

by, if desired, both doors must be closed before the car can be started. The improved control is shown in connection with a hydraulic or air power supply system, but it will be understood that it is readily susceptible for use with other systems of power supply.

One embodiment of the invention is illustrated in the accompanying drawings. 65

The views of the drawings are as follows:

Figure 1 is a front elevation of the control mechanism, the elevator shaft being shown in section and the elevator being indicated in dotted lines. 70

Fig. 2 is a front elevation of the elevator showing the parts of the control mechanism which are carried by the elevator car.

Fig. 3 is an explanatory figure showing the manner in which the cable is deflected 75 when the car door is opened.

Fig. 4 is a horizontal section showing the means carried by the car door for operating the cable and also showing the interlock between the car door and the shaft 80 doors.

Fig. 5 is a sectional view of the valve which is operated by the cable.

Fig. 6 is a vertical section showing the manner in which the weight at the end of 85 the cable is mounted.

Fig. 7 is a vertical section of the motor that renders the elevator operating means operative and inoperative, and

Fig. 8 corresponds with Fig. 7 showing the 90 parts in the position which they assume when the elevator operating means has been shifted to and is locked in its inoperative position.

An elevator shaft A provided with doors 95 B at each landing has an elevator car C adapted to travel up and down therein. A wire rope, cord, or tape D, preferably of high tensile strength and of flat cross-section, as for example a tape of high tension steel, is suspended vertically from top to bottom of the shaft A adjacent to a door E of the car C. The cable D is fastened at its upper end at a point in the shaft above the highest point the top of the car ascends to 100 as the car travels in the shaft A, and is kept under proper tension in any suitable manner. In the embodiment illustrated the tension is provided by a weight F fastened to the lower end of cable D and guided by guides 105 G. In the hydraulic type of elevator chosen for illustration the cable controls a fluid

motor which, in turn, controls the elevator operating means although it will be readily understood that the cable may control by other than hydraulic or fluid pressure means.

- 5 The condition of cable D governs or controls the operation of the elevator car through a three-way fluid pressure valve H. Valve H controls the pressure fluid which operates a differential fluid pressure motor 10 to be hereinafter described. An operating lever h, of valve H has a pin-and-slot connection either with cable D or with the weight F. Usually it is more convenient to connect the lever h with the weight F, as 15 shown in Figs. 1 and 6.

At a suitable point adjacent to the elevator car door E is fastened a bar J, carrying a roller K to actuate the cable D by deflecting the same when the door E is opened.

- 20 When the car door E is of the ordinary folding type the bar J is preferably secured to the door E near its outer side, where the motion of the door is the more rapid; and to increase the effect on the flexible cable D, 25 the cable is preferably guided by guide rollers L, L pivoted at the top and bottom of the elevator car C. These rollers contact with the cable D on the opposite side thereof from that on which the roller K contacts. 30 The cable D preferably threads through a yoke at the end of the bar J, in which yoke the roller K is pivoted.

It will be evident from the foregoing description, that, when the door E is open, 35 the cable D will be deflected between the rollers L, L and its lower end and also the weight F will be drawn up, and, therefore the valve H will be correspondingly operated. This operation of the valve H will 40 cause the operation of the differential motor and the locking or releasing of the means for starting the car in the manner herein-after described.

The valve H is connected with a pipe m, 45 supplying operating fluid under pressure, which fluid is preferably but not necessarily compressed air, from a suitable air compressor or storage reservoir. Pipe m is also connected with a cylinder O. The valve H 50 is also connected by pipe o with a larger cylinder P, and with an exhaust n. The valve and pipes are so arranged that the pressure fluid is always admitted into the smaller cylinder O, but is only intermittently admitted to the larger cylinder P, and when the valve H shuts off the fluid from the cylinder P it opens this cylinder to the exhaust n.

Pistons R and S operate in the cylinder 60 O, P and have piston rods r, s which are respectively connected by pin and slot connections with the opposite ends of a lever T, fulcrumed at t on a standard t' in a convenient position to be oscillated by the movement of the pistons R, S. One end of the

lever T, is connected to the piston rod r, and carries a roller Z, which is adapted to engage a cam U fastened on the sheave V, which sheave is adapted to be operated in the usual manner by means of a cable W by 70 the attendant in the car C, to start and stop the car. The mechanism controlled by sheave V for operating the car is not shown since any of the well known types may be employed. The cam U is provided with a 75 cam groove, the walls u—u' of which are so shaped that the entrance of the roller Z into the cam groove will force the cam and sheave to the middle position and lock the sheave against movement. The cam groove 80 is formed at its inner part with a socket for the roller Z.

While this invention is adapted to prevent the starting of an elevator car when the inner, or car door, is opened, it is also 85 arranged so as to insure the closing of the outer or shaft doors,—that is, doors opening into the shaft A at landings,—before the car can be started up or down from a landing. To effect this, in cases where the outer 90 doors are closed by hand by the elevator attendant, I place on the outside of the inner or car door a flange Y extending vertically from top to bottom of the inner door, in such a position as to contact with a lug or roller 95 X on the inside of the outer or shaft door B, when the inner door is closing. The top and bottom ends of the flange Y, are beveled as shown, in order to lessen the shock of contact of the flange Y with the lug X when 100 the car C is ascending or descending.

The operation is as follows, assuming that the car C is at a landing and that the car door E as well as the shaft door B are open.

In this position the cable D will have been 105 deflected as hereinbefore explained, and therefore the valve H will have been thrown to the position wherein the fluid pressure will have been cut off from the larger cylinder P, and the cylinder P will have been 110 connected with the exhaust n. Therefore, the pressure of the operating fluid on the relatively smaller piston R of the smaller cylinder O will shift the piston R to the position shown in Fig. 8, and the cam U and 115 sheave V will have been forced to their middle position, the car stopped, and the sheave V locked, so that the car cannot be started again until the sheave V is released. If now the elevator attendant closes the 120 elevator car door E the flange Y on the door E contacts with the lug or roller X on the outer or shaft door B, and forces the shaft door also to fully close and latch. As the car door E comes to its closed position, the 125 cable D straightens under the pull of weight F, and the valve H is shifted to a position wherein the fluid pressure is admitted to the larger cylinder P and the exhaust n is closed. Now the pressure of the operating 130

fluid on the larger piston S is greater than the pressure of the fluid on the smaller piston R, and the lever T is oscillated so as to withdraw the cam roller Z from the cam groove, whereby the sheave V is released and is free to be moved by the elevator car attendant through the cable or shipper W. The attendant by his hand cable or shipper W can now start the car in the usual manner. 5 When the car comes to a landing the elevator car attendant stops the car by operating his hand cable W so as to bring the sheave and cam to the middle position. Then as he opens the car door the cable D is deflected, 10 and the valve H is thrown to a position whereby the fluid pressure is cut off from the larger cylinder P, and the exhaust is opened as hereinbefore described. Now the fluid in the smaller cylinder O lifts the piston R and forces the roller Z into the cam groove, thereby locking the cam U and the sheave V so that the attendant cannot start the car until the door E, as well as the door R is closed again. 15

25 It will of course be understood that the outer or shaft doors B may be arranged to be closed by any suitable door closing device, instead of by hand.

Now having described my improvements, 30 I claim as my invention.

1. The combination with an elevator controller of means for rendering the controller operative and inoperative, a cable extending along the hatchway for operating said means, and means whereby the elevator car door may operate said cable in any position of the elevator.

2. The combination with an elevator and operating means therefor, of a cable extending along the hatchway and operated by the elevator car door, and means controlled by said cable for controlling said operating means.

3. The combination with elevator power supplying means, of means for rendering the same operative and inoperative, a cable extending through the hatchway for operating said last named means, and means whereby the elevator car door may operate said cable in any position of the elevator.

4. The combination with elevator power supplying means, of means for rendering the same operative and inoperative, a cable extending through the hatchway for operating said last named means, means whereby the elevator car door may operate said cable in any position of the elevator, and means for preventing closing of the elevator car door until the hatchway door is closed.

5. The combination with an elevator of means for controlling the power supply to the elevator operating means, said means having an operating sheave provided with a cam recess therein, a coöperating cam arm 65 having means for operating it to positively

move the power controlling means to a position to shut off the power and locking it therein, said cam operating means being controlled by the elevator car door so that when the car door is opened the power is 70 positively shut off and the power controlling means locked against operation until the car door is closed.

6. The combination with an elevator of means for controlling the power supply to 75 the elevator operating means, said means having an operating sheave provided with a cam recess therein, said sheave being controlled from the elevator car, a coöperating cam arm having means for operating it to 80 positively move the power controlling means to a position to shut off the power and locking it therein, said cam operating means being controlled by the elevator car door so that when the car door is opened the power 85 is positively shut off and the controlling means locked against operation until the car door is closed.

7. The combination with an elevator of means for controlling the power supply to 90 the elevator operating means, said means being controlled from the elevator car and having a cam surface associated therewith, a coöperating cam, a hydraulic cylinder of relatively small size by which said cam is 95 biased to a position to positively move and lock said power controlling means in a position to shut off the power, a hydraulic cylinder of relatively large size for also controlling said cam and which acts to move 100 the cam to a position to unlock said power controlling means, a controlling valve for controlling the power supply to said cylinders, a cable for actuating said controlling valve and extending through the elevator 105 hatchway, a weight for maintaining said cable in a substantially perpendicular line when the car door is closed so that the controlling valve admits power to both cylinders and unlocks the power controlling means, the car door being arranged to move the cable laterally to shorten its effective 110 length as the car door is opened to thereby allow the relatively large cylinder to exhaust whereby the small cylinder positively 115 causes the power controlling means to be moved to a position to shut off the power and locked therein.

8. The combination with a hydraulically-operated elevator of a valve for controlling 120 the power supply to the elevator operating means, a sheave for controlling said valve and operated from the elevator car, a cam recess in said sheave, a pivoted cam arm co-operating with said recess, a hydraulic cylinder of relatively small size for biasing the cam arm into the recess to positively move and lock the sheave in a position to shut off the power, a hydraulic cylinder of 125 a relatively large size for moving the cam 130

from said recess to unlock said sheave, a controlling valve for controlling the supply of power to said cylinders, a cable in the elevator hatchway for controlling said controlling valve, a weight for normally maintaining said cable in a substantially perpendicular line so that the controlling valve is normally biased to a position to admit power to both cylinders whereby the large cylinder overcomes the smaller and unlocks the sheave, said cable being interlaced with the elevator car door so that when the car door is opened the cable is moved laterally and its effective length shortened to move the controlling valve to allow the large cylinder to exhaust so that the small cylinder may positively move the sheave to a position to shut off the power and lock it therein.

9. The combination with an elevator car and means under the control of the car attendant for controlling the up and down movement thereof, of mechanism for rendering said means ineffective for controlling the raising and lowering of the elevator car, a cable extending along the elevator hatchway for controlling said mechanism, and

means influenced by the elevator car door for operating said cable.

10. The combination with an elevator car and a controller for controlling the operation thereof, of a cable extending along the elevator hatchway and affected by the opened and closed condition of the elevator car door, and means co-operating with said controller and said cable for preventing the operation of the controller when the car door is open and allowing the operation of the controller when the car door is closed.

11. The combination with an elevator and operating means therefor, of a member extending along the hatchway and actuated by the elevator car door, and means controlled by said member for controlling said operating means.

Signed at New York city, in the county of New York, and State of New York, this 19th day of November, A. D. 1913.

EDWIN F. BANFIELD.
